Int. Cl. D10—07

U.S. Cl. D42—1 B

FIG. 1 is a front elevational view of a time indicating face for a horologe showing my new design, the rear being substantially identical thereto.

The ornamental design for a time-indicating face for FIG. 2 is a side elevational view thereof;

FIG. 3 is an edge elevational view thereof.

The drawings are shaded for color contrast.

I claim:

The ornamental design for a time-indicating face for a horologe, as shown and described.
